Application filed July 2, 1900. Serial No. 22,357. Term of patent 14 years.

To all whom it may concern:

Be it known that we, JOSEPH COLDWELL and CHRISTOPHER GILES GILDARD, citizens of the United States, residing at Fall River, 5 in the county of Bristol and State of Massachusetts, have invented and produced a new and original Design for Drop-Bars, of which the following is a specification, reference being had to the accompanying drawings, forming part thereof.

Figure 1 is an elevation or face view of our new design in drop-bars for looms. Fig. 2 is an edge elevation of the same.

As shown in the drawings, the design consists of a drop-bar of substantially oblong 15 shape having rounded ends, and within the area of the edges of which, near said ends, are

formed substantially circular eyes or openings *a* and a narrow slot *b*, connecting said eyes, and therefore extending substantially throughout 20 the length of the bar.

Having described our invention, what we claim is—
